UNITED STATES PATENT OFFICE.

WILLIAM B. RUGGLES, OF BAYONNE, NEW JERSEY.

DRIER.

1,171,143.

Specification of Letters Patent. Patented Feb. 8, 1916.

Application filed June 11, 1909. Serial No. 501,453.

To all whom it may concern:

Be it known that I, WILLIAM B. RUGGLES, a citizen of the United States, residing at Bayonne, in the county of Hudson and State of New Jersey, have invented certain new and useful Improvements in Driers, of which the following is a full, clear, and exact description, such as will enable others skilled in the art to which it appertains to make and use the same.

This invention relates to driers and with regard to the more specific features to that style of apparatus in which the material to be dried does not come in direct contact with the heating medium.

One of the objects of the invention is to provide a drying apparatus of the above general character which will be practical, simple in construction, comparatively cheap to manufacture and highly efficient in operation.

Another object of the invention is to provide a drying apparatus with suitable, improved means for conveying the heating medium through the apparatus, and means for holding the conveying means in place.

Another object of the invention is to provide a drying apparatus with suitable means for withdrawing the steam and moisture given off by the material to be dried during the drying operation.

Another object of the invention is to provide a drier with suitable means for conveying the material to be dried well into the drying chamber, and prevent the same from spilling out the front end thereof.

Another object of the invention is to provide a drying apparatus with means for receiving and collecting the material after the same is dried.

Another object of the invention is to provide a drier of the above character with means whereby a more perfect combustion of the heating medium will take place as the same passes through the drier.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings wherein is shown two of various possible embodi-

ments of the invention: Figure 1 is a side elevation of one complete form of drying apparatus showing certain details and concealed parts in dotted lines and broken away portions. Fig. 2 is a plan view of the same. Fig. 3 is a vertical sectional view showing certain details. Fig. 4 is an end view of the drying apparatus taken on the line $x-x$, Fig. 1 or 3. Figs. 5 and 6 are sectional and elevation views, respectively, of a detail of another form of apparatus. Fig. 7 is an elevation of a discharging chamber. Fig. 8 is a longitudinal sectional view of a modified form of drying apparatus; and Fig. 9 is a compound transverse and sectional view taken on lines $Y-Y-Z-Z$ of Fig. 8.

Referring now in detail to these drawings, and particularly the modification shown in Figs. 1 to 4, inclusive, wherein similar references refer to similar parts throughout the several views of the drawings, 1 denotes the furnace or source of heat of any suitable style, having a discharge flue 2 extending into the front end of the rotatable drum or drying chamber 3 to prevent short-circuiting of hot gases between furnace and fan without passing through the drum. This drum 3 is provided with a central longitudinal flue 4, through which the heating medium from the furnace passes to the opposite end thereof, where it enters an annular header 5 having arranged about its periphery a plurality of smaller tubes or flues 6 adapted to convey the heating medium back to the front end of the drum where it is discharged into an annular hood 7 connected by means of a conduit 8 to an exhaust fan 9 mounted over the furnace 1 as shown clearly in Figs. 1 and 2. The ends of the central flue 4 and the return flues 6 are so connected with the header and a front tube plate 10 as to permit a longitudinal expansion and contraction thereof under varying temperatures. The return flues 6 are supported from the central flue 4 and also the wall of the drum 3 by means of suitable supports (11) which are so connected with the flues as to permit a longitudinal movement thereof as the same expand or contract.

Near the rear or discharge end of the drum, through the outer wall thereof, are a plurality of openings 12 through which the dried material is adapted to pass as the drum rotates. Surrounding the drum at

this point is an annular chamber 13 Fig. 7 having a hopper bottom 14 adapted to collect the dried material. A sliding door 15 is provided at the bottom of the hopper to permit a removal of the material collected therein.

The discharge flue 2 from the furnace extends slightly into the front end of the drum 3, and is preferably surrounded by an annular sleeve 16 of the central flue 4 in the drum 3. Between this sleeve and the furnace flue 2 is a sufficient space, not only to avoid friction between the rotating sleeve and the stationary flue, but to permit the entrance of a certain amount of air to the flue 4 to effect a more perfect combustion of the heating medium as it passes through the flues within the drum. About this point of connection is provided the stationary hood 7 supported upon suitable legs 17 resting on a foundation as shown in Fig. 4, and the walls thereof are adapted to have a sliding contact with the outer periphery of the drum and sleeve, as shown at 18 and 19, Fig. 3. It will be understood by referring to this figure that as the drum rotates, the annular sleeve from the central flue and a partition 20 carried by the drum have a comparatively close or sliding contact with the walls of the hood.

The annular partition 20 is connected to the front tube plate 10 about midway between the annular sleeve 16 of the flue 4 and the wall of the hood 7 forming a receiving chamber 21 for the gases and moisture derived from the material as the same is dried and also a chamber 22 into which the heating medium is discharged. At one side of this chamber 21 passing through the outer end wall and the inner tube plate, is a screw conveyer 23 adapted to carry the material to be dried well into the drying chamber, while, at the opposite side, as shown in Fig. 2, is a branch pipe 24 from the exhaust fan conduit 8, having a damper or regulating means 25, whereby the steam and moisture expelled from the material being dried, is carried along by air currents passing through the drum from the discharge opening 12 to the chamber at the front end thereof. It will be observed that the conveyer 23 is so disposed that the entering material is discharged from the conveyer onto the inner surface of the drum, passing by the adjacent portion of the rotatable flue 4 without contact therewith. This makes for more efficient operation than where the material is permitted to contact or fall on the rotatable flue on entering, as there is then a tendency for some of the material to accumulate and be retained on this portion of the flue.

The drum 3 is provided about its outer wall with an annular ring 26 provided with teeth meshing with a pinion 27, adapted to be rotated through suitable connecting means by a motor 28, as shown in Fig. 2.

There are also provided suitable annular rings 29 having plain surfaces adapted to rest on the sets of rollers 30 mounted beneath the drum. The sides of one of these rings, or both if desired, are engaged by horizontally disposed rollers 31 adapted to prevent a longitudinal movement of the drum.

By an arrangement of belts 32 and pulleys 33 Fig. 2, the conveying apparatus 23 and the exhaust fan 9 are driven simultaneously from the same motor.

The operation of this apparatus should be largely obvious from the above description, but will, nevertheless, be set forth, in brief, as follows: Assuming that a suitable fire has been built within the furnace 1 and the hot gases have passed through the flues 4 and 6 of the drum to thoroughly heat the same, the drum 3 is then rotated by means of the motor 28 and gearing, above described. The material to be dried is then fed into the hopper of the screw conveyer 23 which is driven preferably by the same motor, above mentioned, which carries the material through the hood 7 and front tube plate 10 to the interior of the drum 3 where it falls on the heated return flues 6 at the side thereof. As these flues rotate with the drum they carry the material upwardly and allow the same to fall by gravity on to the center flue 4, from which it again falls to the bottom of the drier. The drum, being slightly inclined with respect to the horizontal, gradually conveys the material the entire length thereof as it rotates until it passes through the openings 12 at the opposite end into the stationary receiving chamber or hopper 14 from which it may be removed when desired. The suction fan 9 not only insures a rapid passage of the heating medium through the flues, but also causes a current of air to pass through the drum from the discharge end thereof in a direction opposite that to which the material is fed, thereby carrying off all the steam and moisture expelled from the material as the same is dried.

Referring now to the modification as shown in Figs. 8 and 9, which illustrates a form of drier similar to that shown in the first modification in general principle and operation, but of a smaller size, the source of heat or furnace 1 is similar to that illustrated in connection with the first modification, but the drum, however, instead of being provided with a main central flue of relatively large diameter, is provided with a plurality of smaller flues 34 arranged annularly about the interior of the drum. These flues are connected at one end to a suitable tube plate or baffle plate 35 of vitreous material in a manner adapted to permit a contraction or expansion of the same under varying degrees of temperature.

The opposite ends of these tubes discharge into an annular header 36 similar to that illustrated in Fig. 1. Circumferentially arranged about these receiving flues is a 5 second series of return flues 37 similarly connected with the header 36 and the tube plate 35 at the forward end. Supports 37' are also provided between the tube plate and the header for holding the flues in relative position and so connected therewith as to permit a sliding or longitudinal movement of the flues in their contraction and expansion to prevent buckling of the same. 10 On the rear face of the baffle plate 35 located at the forward end of the drum 3 is a conical deflecting plate 38 having a plurality of radially projecting partitions 38', as shown clearly in Figs. 5 and 6, adapted to direct the material to be dried falling 15 thereon well into the drum. A similar plate 39 is arranged at the rear end of the drum for discharging the material from the drum after the same is dried. Suitable means are provided about the outer periphery of the 20 drum for rotating the same in a manner similar to that illustrated and described in reference to the first modification. The annular rings 29 co-act with horizontally disposed rollers 31 rotating about vertical 25 pivots to prevent a longitudinal movement of the drum. An annular partition or plate 40 is provided at the front end of the drum connected with the front wall of the baffle plate or tube plate 35, surrounding the flue 30 2 leading from the furnace. A space is preferably provided between this partition and the flue to admit air to the receiving flues 34 to effect a more perfect combustion 35 of the heating medium as the same passes through the drum. Surrounding the point 40 of connection between the drum and the flues 2 of the furnace, is provided a stationary hood 41 having a vertical partition 42 dividing the same into two chambers 43-44. 45 One of these chambers 43 communicates with the ends of the return flues while the other chamber 44 communicates with an annular chamber 45 surrounding one end of the drum into which the material to be dried 50 is fed. The material to be dried is admitted into this chamber through a hopper 46 at one side of the drum, as shown in Fig. 9 whence it is scooped up by buckets 47 mounted on the drum 3 and rotating therewith, and discharged onto the heated pipes when the buckets reach substantially the highest point of their path. An opening 48 is provided in the partition having a suitable damper arrangement, if desired, whereby the moisture expelled from the material is drawn off with the heated products of combustion by the same suction fan 9 mounted on the furnace.

The operation of the apparatus is, in brief, as follows: The heating medium of

the furnace passes through the receiving flues 34 to the header 36 at the rear end of the drum, thence back through the discharge flues 37 to the chamber 43 where it is drawn off by the suction fan 9. The material to 70 be dried is fed into the hopper 46 where it is caught by the rotating buckets 47 and allowed to fall over the heated pipes onto the plate 38 from whence it is shot well into the drum against the heated pipes at the 75 lower part thereof. These pipes scoop up the material, acting thereon as blades, and carry it around the inside of the drum and gradually toward the discharge end thereof. As it collects at the rear end of the drum it 80 is scooped up by the pipes as before, and on reaching approximately the highest point, falls onto the plate 39, from whence it is discharged to the outside of the drier.

As many changes could be made in the 85 above construction and many apparently widely different embodiments of this invention could be made without departing from the scope thereof, it is intended that all matter contained in the above description 90 or shown in the accompanying drawings shall be interpreted as illustrative and not in a limiting sense. It is also to be understood that the language used in the following claims is intended to cover all of the 95 generic and specific features of the invention herein described, and all statements of the scope of the invention which, as a matter of language, might be said to fall therebetween. 100

Having described my invention, what I claim as new, and desire to secure by Letters Patent, is:—

1. In an apparatus of the class described, in combination, a source of combustible 105 heating medium, a drum, a flue therein, rotatable therewith, open at the front end and communicating with said source of heat, and a second flue connected with said first mentioned flue at the rear end thereof 110 adapted to convey the heating medium back to the front end of said drum whereby the material to be dried may pass through said drum out of contact with the heating medium. 115

2. In an apparatus of the class described, in combination, a source of combustible heating medium, a drum, a flue therein open at the front end and communicating with said source of heat, a header at the opposite 120 end into which said flue passes, and a second flue parallel with said first flue extending from said header to the front end of said drum whereby material may be dried within said drum without coming in contact with the heating medium. 125

3. In an apparatus of the class described, in combination, a source of heat, a rotating drum, a central longitudinal flue in said drum through which the products of com- 130

- 5 bumption pass connected with said source of heat at one end, a header in said drum at the opposite end thereof, and a plurality of return flues located about said central flue for conveying the products of combustion back to the front end of said apparatus.
- 10 4. In a device of the class described, in combination, a source of heat, a rotatable drum, a central longitudinal flue connecting with said source of heat extending through said drum, a header at the opposite end of said drum into which the products of combustion are discharged, a plurality of return flues located about said central flue connected with said header and with the front end of said apparatus, and supports for said flues connected to the inner periphery of said drum.
- 15 5. In an apparatus of the class described, in combination, a source of heat, a rotatable drum, a central longitudinal flue connected with said source of heat for conducting a heating medium through said drum, a plurality of return flues located about said central flue and connected therewith adapted to convey the heating medium back to the front end of said drum, and a tube plate for holding said flues in proper relative position and forming a closure for said drum.
- 20 6. In an apparatus of the class described, in combination, a substantially horizontally disposed rotatable drum, a plurality of flues within said drum adapted to form a continuous passage for the heating medium there-through, means for introducing material to be dried into one end of said drum and openings provided at the opposite end of said drum to permit the discharge of the material after the same has been dried, means for collecting said material, and means for rotating said drum.
- 25 7. In an apparatus of the class described, in combination, a substantially horizontally disposed rotatable drum, a source of heat having a suitable stationary flue, a central longitudinal flue within said drum and rotatable therewith, adapted to surround the first-mentioned flue, and means for conveying the heating medium discharged at one end of said central longitudinal flue back to the front end of said drum.
- 30 8. In an apparatus of the class described, in combination, a source of heat having a stationary flue, a substantially horizontally disposed rotatable drum having a central longitudinal flue, an extension on said longitudinal flue surrounding said first mentioned flue, a plurality of flues about said central longitudinal flue connected therewith at the rear end of said apparatus, a tube plate at the front end of said drum for holding said flues in relative position, and an annular partition connected with said tube plate forming a chamber adapted

to receive the heating medium after it has passed through said apparatus.

9. In an apparatus of the class described, in combination, a substantially horizontally disposed rotatable drum and central longitudinal flue, a plurality of flues surrounding said first mentioned flue and connected therewith at one end, and an annular chamber formed at the opposite end of said drum into which the heating medium is discharged after passing through said drum.

10. In an apparatus of the class described, in combination, a substantially horizontally disposed rotatable drum, a central longitudinal flue, a plurality of flues surrounding said central flue and connected therewith at one end of said drum, a tube plate for holding said flues in relative position and furnishing communication between said flues, and an annular space in said tube plate to permit the admission to the interior of said drum of the material to be dried.

11. In an apparatus of the class described, in combination, a substantially horizontally disposed rotatable drum, a central longitudinal flue, a plurality of smaller flues surrounding said first-mentioned flue, a header at one end of said drum connecting said flues to form a continuous passage for the heating medium and furnishing communication between said flues, and a tube plate at the opposite end of said drum having an annular space between the central and outer flues to permit the admission to the drum of the material to be dried.

12. In an apparatus of the class described, in combination, a substantially horizontally disposed rotatable drum having a central longitudinal flue and a plurality of smaller flues between said central flue and the inner wall of said drum, a tube plate at one end of said drum for holding said flues in relative position, and means to permit an expansion of said flues in said tube plate under varying degrees of temperature.

13. In an apparatus of the class described, in combination, a rotatable drum, a central longitudinally disposed flue, a plurality of flues about said central flue, a header forming a connection between said flues for the passage of the heating medium there-through, said flues connected with said header in a manner to permit an expansion or contraction thereof under varying degrees of temperature.

14. An apparatus of the class described, in combination, a rotatable drum having a central longitudinally disposed flue, a plurality of flues about said first-mentioned flue, a tube plate at one end of said drum, and a header at the opposite end of said drum forming a connecting passage between said flues, said flues being connected with said tube plate and said header in a manner to permit an expansion or contraction of

the same under varying degrees of temperature.

15. In an apparatus of the class described, in combination, a substantially horizontally disposed rotatable drum, a central flue, a plurality of flues about said central flue, a header at one end of said drum connecting said flues adapted to form a circuitous passage for said heating medium through said drum, said drum having a plurality of discharge openings in its outer wall, and a hopper surrounding said openings to collect the material as it is discharged.

16. In an apparatus of the class described, 15 in combination, a plurality of flues within said drum adapted to form a circuitous passage for the heating medium therethrough, a tube plate at one end of said drum having an annular space therein to permit the admission of the material to be dried, an annular partition on said tube plate, and an extension to one of said flues co-acting with said annular partition to form a chamber through which the material to be dried is 20 adapted to pass.

17. In an apparatus of the class described, in combination, a substantially horizontally disposed rotatable drum, a plurality of flues within said drum forming a circuitous passage for the heating medium therethrough, a header at one end of said drum, a tube plate at the opposite end adapted to hold said flues in relative position, said flues being connected with said header and said 30 tube plate in a manner to permit a contraction or expansion of the same under varying degrees of temperature, and intermediate means between said header and said tube plate adapted to hold said flues in relative 35 position.

18. In an apparatus of the class described, in combination, a source of heat, a stationary hood, and a rotatable drum having an extended portion thereof interposed between 45 said source of heat and the walls of said stationary hood.

19. In an apparatus of the class described, in combination, a source of heat, a substantially horizontally disposed rotatable drum 50 having an extended portion and a stationary hood, the extended portion of said rotatable drum interposed between said source of heat and said stationary hood.

20. In an apparatus of the class described, 55 in combination, a substantially horizontally disposed drum, a source of heat, a stationary hood and annular partitions on said drum co-acting with said hood and said source of heat to form a chamber within 60 said hood.

21. In an apparatus of the class described, in combination, a rotatable drum, a source of heat, a stationary hood and a plurality of annular partitions surrounding said 65 source of heat co-acting with the walls of

said hood to form a plurality of chambers therein.

22. In an apparatus of the class described, in combination, a substantially horizontally disposed rotatable drum, a source of heat, a stationary hood, a partition, said drum, said partition and said hood co-acting to form a plurality of annular chambers, a suction fan, and means connecting one of said chambers with said fan.

23. In an apparatus of the class described, in combination, a substantially horizontally disposed rotatable drum, a source of heat, a stationary hood, a partition, said drum, said partition and said hood co-acting to form a 80 plurality of annular chambers, a suction fan and means connecting said chambers with said fan.

24. In an apparatus of the class described, in combination, a rotatable drum, a source 85 of heat, a stationary hood, a partition, said drum, said partition and said hood arranged to form a plurality of annular chambers, a suction fan and means connecting said suction fan with one of said chambers for removing the products of combustion discharged thereunto.

25. In an apparatus of the class described, in combination, a rotatable drum, a source of heat, a stationary hood, a partition, said 95 drum, said partition and said hood arranged to form a plurality of annular chambers, a suction fan and means connecting said suction fan with one of said chambers to remove the moisture given off by the material 100 as the same is dried.

26. In an apparatus of the class described, in combination, a stationary hood, a partition, a rotatable drum, said hood, said partition and said drum co-acting to form a 105 plurality of annular chambers, one of said chambers being adapted to receive the products of combustion after having passed through said drum, the other of said chambers communicating with the interior of said drum, and means connected with said chambers for removing the products of combustion and the moisture given off by the material 110 as the same is dried.

27. In an apparatus of the class described, in combination, a stationary hood, a partition, a rotatable drum, said drum, said partition and said hood co-acting to form a plurality of annular chambers, communicating openings between one of said chambers and the interior of the drum, a suction fan, means connecting said suction fan with said second-mentioned chamber to draw off the moisture given off by the material 115 as the same is dried, and means for 120 regulating the current of air drawn off.

28. In an apparatus of the class described, in combination, a source of heat, a rotatable drum, a stationary hood, a partition, said drum, said partition and said hood co- 130

acting to form a plurality of annular chambers about said source of heat, means for discharging the products of combustion through one of said chambers, the other of 5 said chambers communicating with the interior of the drum to receive the moisture given off by the material as the same is dried, a suction fan, means connecting said suction fan with said chambers, and means 10 for regulating the amount of air drawn through said chambers.

29. In an apparatus of the class described, in combination, a stationary hood, a substantially horizontally disposed rotatable drum, an annular partition connected therewith, the walls of said hood being in a general vertical direction, the walls of said drum and partition being in a general horizontal direction, said walls being in contact and arranged to permit a longitudinal expansion or contraction of the walls of the drum under varying degrees of temperature.

30. In an apparatus of the class described, 25 in combination, a source of heat having a stationary flue, said source adapted to supply combustible gas, a drum having a central longitudinal flue surrounding said first-mentioned flue, thereby providing a 30 space communicating with the atmosphere surrounding said stationary flue to permit the admission of air to said second-mentioned flue to complete the combustion of the gases as they pass through the apparatus.

35. 31. In an apparatus of the class described, in combination, a rotatable substantially horizontally disposed drum having a central longitudinal flue, a source of heat, adapted to supply combustible gas and 40 having a stationary flue projecting into said first-mentioned flue, said flues providing a space therebetween to permit the admission of air into said first-mentioned flue to complete the combustion of the gases as they 45 pass through the apparatus, and means for creating a draft through said flue.

32. In an apparatus of the class described, 50 in combination, a substantially horizontally disposed rotatable drum, a stationary hood, a furnace, a flue, a flue passing longitudinally through said rotatable drum, a flue from the furnace communicating therewith, a plurality of return flues about said central flue for conveying the 55 heating medium back to the front end of the drum and a suction fan mounted on said furnace adapted to remove the products of combustion after having passed through said drum.

60 33. In an apparatus of the class described, in combination, a substantially horizontally disposed rotatable drum, a stationary hood, a furnace, a flue from the furnace communicating therewith, a plurality of return flues about said central flue for 65

conveying the heating medium back to the front end of the drum, a suction fan mounted on said furnace adapted to remove the products of combustion after having passed through said drum, and a branch 70 pipe connected with said suction fan adapted to remove the moisture expelled by the material as the same is dried.

34. In an apparatus of the class described, 75 in combination, a rotatable drum, a stationary hood, a source of heat, a flue connected with said source of heat projecting into said drum, a plurality of flues within said drum connected with the first mentioned flue furnishing a circuitous passage 80 for the heating medium through said drum, and means mounted on said source of heat for drawing the heating medium through said apparatus.

35. An apparatus of the class described, 85 in combination, a substantially horizontally disposed rotatable drum, a source of heat having a flue projecting into said drum, a stationary hood surrounding the connection between said flue and said drum, a plurality 90 of flues within said drum connected with said first-mentioned flue to form a circuitous passage for the heating medium there-through, means mounted on said source of heat for creating a draft through said apparatus, and means connected with said last 95 mentioned means communicating with the interior of said drum for withdrawing the moisture given off of the material as the same is dried.

100 36. In an apparatus of the class described, in combination, a substantially horizontally disposed rotatable drum, a source of heat, a plurality of flues within said drum, a flue connected with said source of 105 heat communicating with said first-mentioned flues to form a circuitous passage for the heating medium through said apparatus, means mounted on said source of heat and communicating with the interior of the 110 drum for withdrawing the moisture given off the material as the same is dried.

37. In an apparatus of the class described, 115 in combination, a source of heat, a substantially horizontally disposed rotatable drum, means for rotating said drum, a plurality of flues for conveying the heating medium circuitously through the drum out of contact with the material to be dried, means for introducing the material to be dried at one 120 end thereof, suction means for creating a draft for the heating medium through said drum and connections whereby all of said before mentioned means are operated simultaneously.

125 38. In an apparatus of the class described, in combination, a substantially horizontally disposed rotatable drum, means for rotating said drum, a conveyer means for introducing the material to be dried into said 130

drum, a suction means for creating a draft to the heating medium through said drum and separately withdrawing the moisture given off by the material to be dried, and 5 means between all of said above-mentioned means whereby the same are operated simultaneously.

39. In an apparatus of the class described, in combination, a substantially horizontally 10 disposed rotatable drum, means for rotating said drum, a conveyer means for introducing the material to be dried into said drum, a suction means for creating a draft to the heating medium through said drum and 15 separately withdrawing the moisture given off by the material to be dried, means for regulating said draft, and connecting means between all of said above-mentioned means whereby the same are operated simultaneously. 20

40. In an apparatus of the class described, in combination, a substantially horizontally disposed rotatable drum, means for rotating said drum, means for introducing the material to be dried through said drum, a plurality of flues within the drum for conveying the heating medium therethrough back and forth out of contact with the material to be dried, and means connecting said rotating means and said introducing means whereby the same may be operated simultaneously.

41. In an apparatus of the class described, in combination, a substantially horizontally 35 disposed rotatable drum, a source of heat connected therewith, a stationary hood surrounding said connection, a plurality of flues within said drum communicating with said source of heat for conveying the heating medium circuitously and out of contact 40 with the material to be dried through said drum, suction means for creating a draft for the heating medium and conveyer means at one end of said drum for introducing the 45 material to be dried thereinto.

42. In an apparatus of the class described, in combination, a substantially horizontally disposed rotatable drum, a source of heat connected therewith, a stationary hood surrounding said connection, means co-acting 50 with the walls of said drum and said hood to form a plurality of annular chambers about said connection, means for introducing the material to be dried through one 55 of said chambers, and means for withdrawing the heating medium through another of said chambers.

43. In an apparatus of the class described, in combination, a substantially horizontally 60 disposed rotatable drum, a source of heat connected therewith, a stationary hood surrounding said point of connection, a plurality of annular partitions co-acting with the walls of said hood and said drum to 65 form a plurality of annular chambers,

means for conveying the material to be dried through one of said chambers, means for withdrawing the moisture given off by the material as the same is dried connected with said same chamber, and means connected 70 with another of said chambers for withdrawing the heating medium after the same has passed through the drum.

44. In an apparatus of the class described, in combination, a substantially horizontally 75 disposed rotatable drum, a source of heat connected therewith, a stationary hood surrounding said point of connection, an annular chamber formed by the walls of said hood and said drum, means for conveying 80 the material to be dried through said chamber, and means communicating therewith for withdrawing the moisture given off by the material as the same is dried.

45. In an apparatus of the class described, in combination, a substantially horizontally 85 disposed rotatable drum provided with discharge openings at one end thereof, a hood surrounding the opposite end of said drum having walls co-acting with the walls of said 90 drum to form an annular chamber, means for introducing the material to be dried through said chamber, suction means connected with said chamber for withdrawing the moisture given off by the material to be 95 dried and for creating a draft through said drum from said discharge opening in a direction opposite that to which said material is passed.

46. In an apparatus of the class described, in combination, a substantially horizontally 100 disposed rotatable drum, means for rotating said drum, a plurality of connected flues within said drum, a source of heat connected with said flues, a stationary hood and 105 partitions co-acting with the walls of said hood and said drum to form a plurality of chambers about the connection between said source of heat and said flues, one of said chambers communicating with said flues 110 into which the heating medium is discharged after passing through the drum, and another of said chambers communicating with the interior of said drum adapted to receive the moisture given off from the 115 material as the same is dried.

47. In an apparatus of the class described, in combination, a substantially horizontally disposed rotatable drum, a plurality of flues therein having sliding connections 120 with the walls of said drum to permit a contraction and expansion of the parts under varying degrees of temperature, a source of heat connected with said flues, a hood surrounding the point of connection between 125 the flues and the source of heat, an annular chamber formed by the walls of said drum and said hood through which the material to be dried is passed, a conveyer for introducing the material, means for rotating the 130

drum, and connecting means between said rotating means and said conveyer means whereby the same operate simultaneously.

48. In an apparatus of the class described, in combination, a substantially horizontally disposed rotatable drum, a source of heat connected with said drum, a hood surrounding the point of connection between said parts, a tube plate located at one end of said drum and a header at the opposite end, a plurality of flues supported by said tube plate and said header arranged to have a sliding connection therewith permitting the contraction and expansion of the flues under varying degrees of temperature, an annular partition connected with said tube plate dividing said hood into a plurality of chambers, one of said chambers communicating with said flues, another of said chambers communicating with the interior of the drum, and means for withdrawing the heating medium from one of said chambers, and the moisture from the material to be dried from the other of said chambers.

49. In an apparatus of the class described, in combination, a source of heat, a drum flue openly connected therewith, a fan for driving the heating medium through the drum flue to a point without the same, and means surrounding said connection to prevent a short-circuiting of the heating medium to the fan at the point of connection between the drum flue and the source of heat.

50. In apparatus of the class described, in combination, a source of heat, a drum, a flue associated therewith and connected with the source of heat, and means providing for combustion in the flue.

51. In an apparatus of the character described, in combination, a drum, a source of heat having a flue projecting into said drum for conveying the heating medium thereto, and a flue within said drum having a portion thereof surrounding the flue from said source of heat, said flues being sufficiently spaced to permit the admission of air to effect a more perfect combustion of the heating medium as the same passes through the drum.

52. In an apparatus of the character described, in combination, a horizontally disposed, rotatable drum, a source of heat having a flue projecting into said drum, and a longitudinal flue within said drum and rotatable therewith, a portion of which surrounds the flue connected with said source of heat and being of larger diameter than the body portion of said flue, said rotatable flue being so disposed with respect to the stationary flue as to permit a longitudinal expansion and contraction thereof under varying degrees of temperature.

53. In an apparatus of the character described, in combination, a rotatable drum

having a longitudinal flue, a source of heat, a flue connected therewith and projecting into said first mentioned flue forming a space between the same for the admission of air to said first mentioned flue, a hood surrounding the point of connection between said flues, and means for conveying the material to be dried into said drum at one side of said point of connection.

54. In an apparatus of the character described, in combination, a source of heat, a rotatable drum, a central longitudinal flue therein, a flue connecting said source of heat to said drum and projecting into said central flue, the portion of said first mentioned flue surrounding the second mentioned flue being of larger diameter than the body portion thereof.

55. In an apparatus of the character described, in combination, a drum, a source of combustible heating medium, and a flue construction having a portion for conveying said combustible heating medium from one end to the other end of said drum and another portion for returning said heating medium toward said first-mentioned end.

56. In an apparatus of the class described, in combination, a hood, a rotatable drying drum, one end of which communicates with said hood, a flue mounted in said drum and communicating with said hood, and a second flue in said drum communicating with said first flue and out of direct communication with said hood.

57. In an apparatus of the class described, in combination, a hood, a rotatable drying drum, one end of which communicates with said hood, a flue mounted in said drum and communicating with said hood, a second flue in said drum communicating with said first flue and out of direct communication with said hood, and a pipe adapted to lead a heated current to said second flue.

58. In an apparatus of the class described, in combination, a hood, a rotatable drying drum, one end of which communicates with said hood, a flue mounted in said drum and communicating with said hood, a second flue in said drum communicating with said first flue and out of direct communication with said hood, and a pipe comprising a portion within and transversely spaced from said second flue adapted to lead a heated current thereto.

59. In an apparatus of the class described, in combination, a hood, a rotatable drying drum, one end of which communicates with said hood, a flue mounted in said drum and communicating with said hood, a second flue in said drum communicating with said first flue, said second flue having a concentric portion of different diameter passing through said hood, and a pipe comprising a portion within said portion of different diameter and spaced longitudinally from

the shoulder formed by the different sized portions of said second flue.

60. In an apparatus of the class described, in combination, a hood, a rotatable drying drum, one end of which communicates with said hood, a flue mounted in said drum and communicating with said hood, a second flue in said drum communicating with said first flue at a point adjacent the opposite 5 end of said drum and out of direct communication with said hood, draft-producing means, and passageways connecting said draft-producing means with said hood and the interior of said drum, respectively.

10 61. In an apparatus of the class described, in combination, a hood, a rotatable drying drum, one end of which communicates with said hood, a flue mounted in said drum and communicating with said hood, a second flue 15 in said drum communicating with said first flue at a point adjacent the opposite end of said drum and out of direct communication with said hood, draft-producing means, passageways connecting said draft-producing 20 means with said hood and the interior of said drum, respectively, and means adapted to control the draft through the passageway 25 communicating with said drum.

62. In an apparatus of the class described, 30 in combination, a stationary hood having spaced upright walls and inner and outer concentric chambers, a substantially horizontal rotatable cylindrical drum extending within an upright wall of said hood and 35 communicating with the inner chamber of said hood, a centrally disposed, longitudinal flue mounted on said drum and extending through said walls of said hood, and a plurality of longitudinal flues carried by 40 said drum around said central flue, said plurality of flues opening into said outer chamber at one end and communicating with said central flue at their opposite ends.

63. In an apparatus of the class described, 45 in combination, a hood comprising a plurality of chambers, a rotatable drying drum, the interior of which communicates with one of said chambers at one end, a flue mounted in said drum and communicating 50 with another of said chambers, a second flue in said drum communicating with said first flue at a point adjacent the opposite end of said drum and out of direct communication with said hood, and means passing through 55 one of said chambers adapted to charge the drum with material to be dried.

64. In an apparatus of the class described, 60 in combination, a stationary hood having spaced upright walls and inner and outer concentric chambers, a substantially horizontal rotatable cylindrical drum extending within an upright wall of said hood and communicating with the inner chamber of said hood, a centrally disposed longitudinal flue mounted on said drum and extending

through said walls of said hood, a plurality of longitudinal flues carried by said drum around said central flue, said plurality of flues opening into said outer chamber at one end and communicating with said central flue at their opposite ends, and means passing through said inner chamber adapted to charge the drum with material to be dried. 70

65. In an apparatus of the class described, in combination, a stationary hood having 75 spaced upright walls, a substantially horizontal rotatable cylindrical drum extending within an upright wall of said hood at one end, a central longitudinal flue carried by said drum and extending through the walls 80 of said hood, a plurality of longitudinal flues carried by said drum around said central flue, said plurality of flues opening into said hood, said drum having a central opening communicating with said hood, and a 85 concentric partition in said hood between the central opening of said drum and the openings of said plurality of flues into said hood.

66. In an apparatus of the class described, 90 in combination, a stationary hood having spaced upright walls, a substantially horizontal rotatable cylindrical drum extending within an upright wall of said hood at one end, a central longitudinal flue carried by 95 said drum and extending through the walls of said hood, a plurality of longitudinal flues carried by said drum around said central flue, said plurality of flues opening into said hood, said drum having a central opening communicating with said hood, and a 100 concentric extension forming a partition in said hood between the central opening of said drum and the adjacent openings of said plurality of flues. 105

67. In an apparatus of the class described, in combination, an upright hood, a substantially horizontal rotatable cylindrical metallic drum extending within a wall of said hood at one end and closely associated with said wall, said drum having a concentric partitioning plate extending toward the opposite wall of said hood and closely associated with said opposite wall, a flue carried by said drum having a concentric portion 110 extending into close contact with said opposite wall, and a series of flues around said central flue, communicating with said hood on one side of said plate and with said central flue adjacent the opposite end of said drum. 115

68. In an apparatus of the character described, in combination, a rotatable substantially horizontally disposed drum, a rotatable longitudinally disposed flue in said drum, a source of heat having a stationary flue adapted to discharge the heating medium into said first mentioned flue adjacent one end portion of said drum, means adjacent said end of the drum adapted to create 120 125 130

a draft from said source of heat through said rotatable flue to the exterior of the drum, said stationary flue and said rotatable flue being so disposed as to provide an opening therebetween adapted to communicate with the atmosphere and said rotatable flue.

69. In an apparatus of the character described, in combination, a rotatable substantially horizontally disposed drum, a rotatable longitudinally disposed flue in said drum, a source of heat having a stationary flue adapted to discharge the heating medium into said first mentioned flue adjacent

one end portion of said drum, a feed opening leading to the space between said drum and flue, and means adapted to guide the entering material past said rotatable flue into said drum without contact with the rotatable flue adjacent the entering path of said material. 15 20

In testimony whereof I affix my signature in the presence of two witnesses.

WILLIAM B. RUGGLES.
